INSTRUMENT FOR THE TREATMENT OF
NASAL PASSAGES

John C. Shotton, Lakewood, Ohio

Application May 16, 1932, Serial No. 611,505

4 Claims. (Cl. 128—211)

This invention relates to an instrument which is primarily designed for the treatment of the nasal passages of persons afflicted with colds or similar ailments.

5 The general purpose and object of the invention is to provide a simple instrument for the foregoing purpose which will automatically control and distribute respiratory fluid (air free from, or laden with, vapors or atomized medicament) 10 to the nasal passages of a patient in a manner to avoid the clogging or partial stoppage of one or both of such passages, the purpose being to so treat the nasal passages as to secure the clearing of both passages and maintain them both in such 15 cleared condition.

I accomplish the foregoing object in and through the instrument shown in the accompanying drawing wherein Fig. 1 shows a side elevation of said instrument; and Figs. 2, 3, 4, 5 and 20 6 are sectional views corresponding respectively to the lines 2—2, 3—3, 4—4, 5—5 and 6—6 of Fig. 1 of the drawing.

The instrument comprises generally a pair of tubes, each having at the delivery end thereof an applicator adapted to be inserted into the nostril of a patient; an automatically operated mechanism for controlling the distribution of air or vapor-laden air to the said tubes in a predetermined manner; and, where the air is to be medicated, as by a vapor, a receptacle from which vapor-laden air may be supplied to the said mechanism and thence to the said tubes.

Describing the instrument disclosed herein by reference characters, 1 represents a base on which 35 is supported a housing 2 the right hand side or front of which is indicated at 3, the left hand or back of which is closed by a valve casing 4 having front and rear walls 5 and 6, the valve casing being also mounted on the base 1. Secured to the 40 front or delivery side 5 of the valve casing is a connecting member 7 having nipples 8 each having a passage 9 therethrough, the rear or left hand ends of the passages merging at their receiving ends with elongated chambers 10. These 45 chambers register with correspondingly elongated openings 11 in the front or delivery side 5 of the valve casing 4. The rear or receiving side of the valve casing is also provided with elongated openings 12.

50 Secured to the rear or receiving side 6 of the casing 4 is a connecting member 13 having passages 14 therethrough, the front or delivery ends of the said passages merging with elongated chambers 15 corresponding in position and shape 55 to and registering with the openings 12 which in

turn register with the elongated openings 11 (see Figs. 3 and 5).

16 denotes generally a receptacle which is detachably applied to the connection 13. The receptacle 16 comprises a cover wall 17, a rear wall 18, side walls 19, and a removable cap 20 for the bottom, this cap having openings 21 therethrough for the passage of air. Where it is desired to medicate the air supplied through the receptacle 16, this result may be obtained by inserting 10 into the receptacle a sponge 22, or other absorbent material, more or less saturated with a liquid capable of emitting vapors to mingle with the air admitted through the said openings.

23 denotes a shaft which is journaled in the 15 front wall of the housing 2 and in the rear wall of the casing 4. Mounted on this shaft is a valve disk 24 having near its periphery ports 25, preferably approximately triangular in shape, the sides of the ports corresponding approximately 20 to radii drawn from the center of the disk. These ports are so arranged as to register with the elongated openings 11 and 12 and with the elongated chambers 10 and 15, the ports being 25 so spaced apart that the portions of the disk 26 between the ports is of sufficient width to cover completely each chamber 11, thereby cutting off air and/or vapor-laden air for a short period of time from each chamber 11 and hence from each 30 passage 9.

The shaft 23 will be driven automatically by any timing mechanism, an ordinary clock-work mechanism being indicated in Fig. 1 and comprising a winding shaft 27 having a spring 28 connected thereto, and shown as provided with an operating knob 27a. This shaft is connected by means of reducing gearing 29, 30, 31, 32, 33 and 34, with the shaft 23, the gears 30 and 31 being mounted on a shaft 35; the gears 32 and 33 being mounted on a shaft 36; and the gear 34 being 40 mounted on the shaft 23.

37 denotes a pair of flexible tubes which are connected respectively to the nipples 8 and each of which is shown as provided with a tapered plug 38 for application to the nostril of the patient. 45 A check valve 39 is provided in each of the tubes 37, the check valves being of any standard type and adapted to be opened by inhalation of the patient and to be closed by exhalation through the nasal passages.

With the parts constructed and arranged as described, the operation will be readily understood. The spring 28 having been wound and the plugs 38 inserted into the nostrils of the patient, air will be drawn through the receptacle 50 55

19 and through the tubes 37 into the nasal passages in the following manner (assuming that the starting position is that indicated in Fig. 4):—
5 through both of the tubes 37; then through one tube only; then through the other tube only; and then through both tubes. Owing to the close juxtaposition of the adjacent ends of the chambers 10 and 15, the patient will at all times receive air (either with or without admixture of
10 a medicament therewith) through at least one nostril. In the drawing the spacing between the openings 11 is such that they are open a very slight degree when each opening 25 spans the space therebetween, but this is so slight that it
15 can be neglected and, if desired, can be prevented by slightly narrowing the width of the openings 25.

Obviously, a spring motor may be employed which will enable the instrument to run for hours
20 without rewinding; or the shaft 27 may be driven by any suitable mechanism which will insure the rotation of the valve for as long a time as is desirable.

The advantage of this instrument is that it
25 corrects largely, if not completely, the tendency of one nasal passage to become clogged, as it insures the distribution of air (whether medicated or not) alternately in like amounts to each of the nasal passages as well as to both nasal passages.
30 This treatment corrects the tendency of one nasal passage to become obstructed because of the temporary freedom of obstruction of the other nasal passage, which would result in depriving the nasal passage thus obstructed from
35 receiving its quota of air.

The instrument can be used by a patient for an indefinite time as, for instance, overnight, without interfering with freedom of breathing, as the check valves 39 prevent exhalation through the
40 nasal passages, allowing the patient to exhale through the mouth while receiving the necessary air (medicated if desired) through the nasal passages and insuring that both of the passages will be maintained free from clogging or obstruc-
45 tion due to the accumulation of mucus.

Having thus described my invention, what I claim is:

1. An instrument of the character described comprising a valve casing having pairs of open-

ings in opposite sides thereof, conduits operatively connected to the openings on one of the sides of the said casing for supplying respiratory fluid to the nostrils of a patient, a rotary disk valve in said casing and interposed between the openings in the opposed side walls thereof, the said disk valve having ports therein adapted to register in repeated cycles successively and then simultaneously with the said openings.

2. An instrument of the character described comprising a valve casing having pairs of openings in opposite sides thereof, the openings in one side being opposed to and registering with the openings in the other side, a receptacle having one or more openings therein for the admission of respiratory fluid and connected with the openings in one of the sides of the said casing, conduits connected with the openings in the other side of said casing, a rotary disk valve in said casing and having intermediate the center and periphery thereof ports adapted to register in repeated cycles successively and simultaneously with the openings in the side walls of the said casing, and then means for rotating the said valve at a substantially uniform rate of rotation for an extended period of time.

3. An instrument of the character described, including a medicament chamber having an air inlet, means defining a pair of passages leading from said chamber to a pair of nozzles adapted to be received in the nostrils of a patient and means for opening and closing said passages in a continuous series of cycles, said means including mechanism for opening both said passages at one point in each cycle and at other points in each cycle opening them one only at a time.

4. In an instrument of the character described, a valve body, means defining a pair of passages leading from said valve body to a pair of nozzles adapted to be received in the nostrils of a patient and a movable valve element cooperating with said valve body, means for moving said valve element in repeated cycles and openings through said valve element adapted to register with said passages to open them at the same time at one point in each cycle and to open said passages one at a time at other points in each cycle.

JOHN C. SHOTTON.
